UNITED STATES PATENT OFFICE.

HARRY WILLSHAW, OF BUFFALO, NEW YORK, ASSIGNOR TO DUNLOP TIRE AND RUBBER CORPORATION OF AMERICA, OF BUFFALO, NEW YORK, A CORPORATION OF NEW YORK.

DESIGN FOR A SOLID TIRE.

Application filed August 7, 1924. Serial No. 10,398. Term of patent 14 years.

To all whom it may concern:

Be it known that I, HARRY WILLSHAW, a subject of the King of Great Britain, a resident of Buffalo, county of Erie, and State of New York, have invented a new, original, and ornamental Design for Solid Tire, of which the following is a specification, reference being had to the accompanying drawings, forming a part thereof.

Fig. 1 is a perspective view of a complete tire.

Fig. 2 is a transverse section of the same.

Fig. 3 is an edge elevation of a portion of the tire, showing tread surface.

I claim:

The ornamental design for a solid tire as shown.

In witness whereof, I have hereunto signed my name.

HARRY WILLSHAW.
